UNITED STATES PATENT OFFICE.

LAURA M. DE SUÁREZ, OF BROOKLYN, NEW YORK.

SHOE FOR RHEUMATISM.

Application filed March 3, 1926. Serial No. 91,933.

This invention relates to antirheumatic shoes and has for its object to provide an article of this character especially adapted to keep the feet dry and warm under any 5 conditions of weather and at the same time ventilated in such a way as to prevent perspiration.

It is further designed to afford means which will give a snug fit around the ankles, 10 but yielding so as to permit ease and facility in putting on, or taking off from the foot.

The shoe is simple and neat in construction and may be manufactured at a cost commensurate with its utility.

Shoes of which the principal elements are rubber and like materials; while desirable for protection against dampness; are known to give great discomfort and to some extent 20 defeat their chief purpose by reason of the excessive heat which they produce in the foot of the wearer, and its accompanying perspiration. The novel means for obviating this difficulty presents a very desirable 25 feature of this invention.

In the drawings;

Fig. 1 shows a perspective view of the shoe.

Fig. 2 shows a fragmentary section on 30 the line 2—2 of Figure 1.

Fig. 3 shows the ventilating strip in the flat.

Fig. 4 shows a fragmentary portion of 35 the strip shown in Figure 3; it being a side elevation to show the button grip member.

Fig. 5 shows a modified form of the ventilating mechanism, in which the covering member is slit lengthwise.

The shoe is constructed as follows;

An upper, or body portion 10 which may be of canvas, leather or any suitable material, is secured to the bottom, or sole member 11, which is preferably of rubber; although other materials may be found adequate 40 for the purpose; the essential feature being imperviousness to water, or dampness. The upper portion is provided with elastic gores as shown at 12 which hold it snugly around the ankle of the wearer, but will stretch sufficiently to permit of removal of the shoe from the foot. The ventilating assembly 45 consists of a flexible adjusting strip 13 which may be of metal, celluloid, or like material. This strip is perforated as shown at 14, 15 etc., and when in position, rests upon the surface of the upper body 10, and

has its perforations in line with similar perforations in the said upper body. A sheath member 16 rests upon the top surface of the strip 13 and has its sides extending outward therefrom and stitched to the upper body 10. This sheath member is also perforated as shown at 17 and 18. A top member 19 rests upon the side portions of the sheath member and is stitched together 65 with the said member to the body of the shoe. The member 19 is slightly raised along its central portion and permits of the free passage of air between it and the sheath member.

It will be seen that with the adjusting strip 13 pushed down to its full extent; the apertures in the various members will register with each other, and air may pass in or out of the shoe through the said apertures; but should the said adjusting strip be moved upward by means of the button 20; the apertures may be partially, or altogether closed, as desired; thus giving any required degree of ventilation.

The cover member 19 provides a channel giving free passage of air to the ventilating apertures, while protecting them from general exposure.

In the modified form shown in Figure 5 85 of the drawings; the cover member is parted longitudinally as shown at 21, thus providing a form of the invention which may be preferred by some individuals.

While I have shown the preferred embodiments of my invention; I do not wish to limit myself to the exact details of construction as shown; but claim the right to such minor modifications as may come within the scope of the appended claims.

Having thus described my invention, what I claim as new and desire to secure by Letters Patent; is as follows:

1. In a shoe of the class described, an upper body of suitable material secured at 100 its lower extremities to moisture proof bottom members, and ventilating means for the said shoe, consisting of a perforated flexible strip slidably mounted on the said upper body and having its perforations in line 105 with, and adapted to cover, or to expose similar perforations in the said upper body at the will of the user.

2. In a shoe of the class described, an upper body of suitable material secured at its 110 lower extremities to moisture proof bottom members, the said upper body having a series

- of apertures therein, a flexible strip member with apertures in alignment with apertures of said upper body, a perforated sheath with said strip member slidably mounted therein,
- 5 5. a covering over the said sheath forming an air channel between the said sheath member and the said covering, and means to adjust the said flexible strip to cover, or to expose the apertures in the said upper body.
- 10 10. 3. In a shoe of the class described, an upper body of suitable material having elastic side portions, and itself secured to bottom members impervious to moisture, the wall of said body having apertures therein, an adjusting strip in line with the said apertures, a perforated sheath with said adjusting strip slidably mounted therein, said adjusting strip having perforations adapted to be brought into position to open, or to close the
- 15 20. apertures of the said body, and a covering over the said sheath forming an air channel between the said covering and the said sheath, substantially as shown and described.
- 25 25. 4. In a shoe of the class described, an upper body of suitable material, having elastic side portions, the said upper body secured at its lower extremities to moisture proof

bottom members, the wall of the said body having apertures therein, a perforated 30 sheath covering, a perforated adjusting strip slidably mounted under said sheath covering, said sheath covering adapted to be moved in such a way as to bring the adjacent perforations of said strip and sheath casing into 35 registration with the apertures of the said upper body, and a slit covering member over said sheath covering and in line with the aforesaid perforations, substantially as shown and described. 40

5. In a shoe of the class described, an upper body of suitable fabric having elastic side portions, and secured at its lower extremities to moisture proof sole members, the forward wall of the said upper body having 45 apertures therein, a perforated adjusting strip mounted in line with the said apertures, a sheath casing supporting said strip, said casing also being perforated, and a protecting covering over said sheath casing and in 50 line therewith, substantially as shown and described herewith.

In testimony whereof I have affixed my signature.

LAURA M. DE SUÁREZ.
